UNITED STATES PATENT OFFICE.

WILLIAM JAMES HAYDEN, OF ATHOL CENTER, MASSACHUSETTS.

MORTISING-MACHINE ATTACHMENT.

No. 849,389.

Specification of Letters Patent.

Patented April 9, 1907.

Application filed October 26, 1906. Serial No. 340,744.

To all whom it may concern:

Be it known that I, WILLIAM JAMES HAYDEN, a citizen of the United States, residing at Athol Center, in the county of Worcester 5 and State of Massachusetts, have invented a new and useful Mortising-Machine Attachment, of which the following is a specification.

This invention relates to mortising-machines of that character utilizing chain-cutters and which are employed for mortising stiles, &c., and the invention is more particularly an attachment for such machines, by the use of which any number of stiles can 10 be mortised at predetermined points thereon without the necessity of marking them off and exercising care in properly placing them under the cutter.

Heretofore in the manufacture of shutter-stiles and similar objects it has been necessary in order to properly mortise them to first lay off the mortise and then carefully place the stile in proper position beneath the cutting-tool, so as to insure the proper location of the mortise. With the present invention, however, after a proper adjustment of the attachment a stile can be placed upon the bed of the machine and fed forward without the exercise of any particular skill 25 and said stile will be held at proper points, so that mortises will be cut thereinto without the necessity of marking off the stiles or exercising any particular care in properly placing them.

Another object of this invention is to provide a novel arrangement of parts whereby mortises of different lengths may be cut within a stile at any points desired.

With these and other objects in view the 40 invention consists of certain novel features of construction and combinations of parts, which will be hereinafter more fully described, and pointed out in the claims.

In the accompanying drawings is shown 45 the preferred form of the invention.

In said drawings, Figure 1 is a perspective view of a portion of a mortising-machine having my improved attachment applied thereto, said attachment being broken away.

Fig. 2 is a plan view of the attachment, the adjoining portion of the machine being in section and the intermediate parts of the attachment being removed. Fig. 3 is a rear elevation of the attachment, a portion of the 55 slide and the bed being shown in section. Fig. 4 is an end view of a portion of the table of

the machine and the slide and the parts connected thereto. Fig. 5 is a perspective view of the latch. Figs. 6, 7, 8, 9, 10, 11, 12, and 13 are detail views showing the successive steps 60 followed in the passage of a double stop through the latch; and Fig. 14 is a perspective view of a finished stile, showing mortises of different lengths therein.

Referring to the figures by characters of 65 reference, 1 is the bed of a mortising-machine of the usual construction, the same having a rear upwardly-extending portion 2, and supported above the bed is a suitably-actuated cutting-chain 3. This bed, as usual, is vertically movable so as to carry a stile from or toward the cutting-chain, and a support 4 is disposed in rear of the table. These parts all constitute elements of the ordinary mortising-machines utilizing cutting-chains, and the present invention is in the form of an attachment for use in connection therewith. Heretofore it has been necessary to mark 70 upon a stile the point or points at which mortises are to be cut, after which the stile is placed on the table 1 with the marks directly under the cutting-chain and the table then moved toward said chain so that the mortise will be cut within the stile. Obviously with this construction considerable care must be 75 exercised and time expended in marking off the mortises and in properly placing the stile on the table. The present invention consists of an attachment which obviates these 80 objectionable features and consists of two 90 primary elements—to wit, a bed attachment A and a latch attachment B. The bed attachment consists of an elongated dovetailed guide-strip 5, which is secured to the back 2 of the table 1 in any preferred manner and on 95 which is mounted a slide 6, which may be of substantially the same length as the stile to be mortised, although it is of course to be understood that this length is not essential.

Secured to the slide 6 adjacent one end is a 100 stop-block 7, the inner or working face of which is concave, as shown at 8, so as to tightly engage the end of a stile and prevent it from being thrown from the table while the cutting-chain is working upon it. The 105 slide 6 projects above the back 2, and secured to the rear face of this upwardly-projecting portion is a longitudinally-extending rod 9, having its ends secured in brackets 10, extending from the slide 6. Adjustably 110 mounted on the rod 9 are a suitable number of stops, which may be of different forms to

produce different results. For instance, the stop may consist of a single finger 11, extending from a sleeve 12, slidably mounted on the rod and adapted to be secured thereon by a set-screw 13. If preferred, however, a double stop may be formed by placing two of these fingers upon the rod close together, as shown at 14. A triple stop may be formed in the same manner by placing three single stops close together upon the rod, or if preferred, such a stop may be formed in a single piece, as shown at 15, the same consisting of a sleeve 16, provided with three projecting fingers 17, said sleeve being adapted to be fastened upon the rod by means of set-screws 18. It will of course be understood that these stops may be placed at any desired points upon the rod 9, their relative positions and their character being dependent upon the distances apart at which the mortises are to be made and the sizes of the mortises. As hereinbefore explained, a single stop will result in the formation of a short mortise, a double stop a larger mortise, &c., the size of the mortise increasing with the number of stops used together.

The bed attachment A, which has been described, is adapted to be used upon a mortising-machine in connection with a latch attachment B of peculiar construction. This latch attachment consists of an angular plate 19, constituting the base of the attachment and which is adapted to be fastened by means of bolts 20 or in any other preferred manner to the support 4 of the machine. A guide-flange 21 extends forward from one edge of the front face of the base 19 and upward from said base, and the lower end of this flange has one face beveled, as shown at 22, while its other face has an angular recess 23, adapted to receive the upper end of a strip 24, which is loosely secured, as shown at 25, to one end of a weight 26. This weight is pivoted, as at 27, upon the base 19 and has an upwardly-extending lug 28, adapted to normally bear against a stop-pin 29, and when the weight is in this position the upper end of the strip 24 is disposed at a point slightly removed from the flange 21, as shown particularly in Figs. 5, 6, 12, and 13. This latch is so disposed upon the fixed support 4 that when the bed is in its lowest position the stops 11, 14, and 15 are in position to pass between the flange 21 and the weight 26.

In using this machine the stops are disposed upon the rod 9 at distances apart equal to the distances between the mortises to be formed within a stile, and if a short mortise is to be formed one stop 11 is placed at the proper point upon the rod 9, whereas if longer mortises are to be cut double or triple stops are secured upon the rod at the proper places. In the present instance I have shown a single, a double, and a triple stop arranged upon the rod so as to form a stile 30, having a short

mortise 31 in one end, a long mortise 32 in the other end, and a mortise 33 of medium length located at a point between the ends of the stile. In forming a mortise of this character table 1 is lowered, and the slide 6 is drawn toward the right of the machine upon the guide-strip 5, and the stops will successively pass over the weight 26 and against the upwardly-extending portion of the strip 24, swinging said strip downward out of their way, so that all of the stops can assume positions to the right of the latch. A stile is then placed upon the bed 1 and against the block 7 and pushed forward or toward the left of the machine, carrying the slide 6 therewith. This movement will be stopped by the first finger 17 of stop 15 coming into contact with the latch-strip 24, swinging it forward into the recesses 23, these positions of the parts being shown in Figs. 6 and 7. The machine is then set in motion, and the bed is immediately raised, carrying the stop upward in the direction of the arrow in Fig. 7 and along the flange 21, and during this upward movement the chain 3 will cut into the slide. As soon as the stop passes on to the flange 21 the strip 24 swings back to its normal position, as shown in Fig. 8, and when the stop moves downward with the bed after the mortise has been cut and, as shown by an arrow in Fig. 8, the first finger thereof will pass over the strip 24 and under the flange 21, and a further push upon the slide 6 will bring the next finger against the strip 24 and force said strip against the flange, as shown in Fig. 10. The two fingers 17 will then pass upward upon the flange 21, one of them being disposed at each side thereof, as shown in Fig. 10, and as they pass upward the cutting-chain will again pass into the stile and elongate the first mortise. When the stops come down after this cutting has been completed, they will pass under the flange 21, as shown in Fig. 12, and if other fingers are formed upon the stop the operation can be continued. After the last finger of the stop has passed under the flange 21 the operator pushes the slide longitudinally toward the left until the finger of the next stop contacts with the latch, whereupon the described operation is repeated.

In Figs. 6 to 13 a double stop only has been illustrated; but the operation of a single or triple stop or, in fact, a stop having any number of fingers will, it is thought, be clearly apparent from an examination of said figures in connection with the foregoing description. It will be noticed that after the stops have once been arranged it is merely necessary for the operator to exert a constant longitudinal pressure upon the slide 6 and the stops will automatically hold the stile at the proper points and for the desired number of cuts, so that mortises will be produced at the proper points and of predetermined lengths. It will be understood that the arm

24^a of the strip 24 constitutes a weight and serves to hold said strip by gravity normally removed from flange 21.

The preferred form of the invention has been set forth in the foregoing description; but I do not limit myself thereto, as I am aware that modifications may be made therein without departing from the spirit or sacrificing the advantages thereof, and I therefore reserve the right to make such changes as fairly fall within the scope of the claims.

What is claimed is—

1. In a mortising-machine the combination with a vertically-movable table and a stop movable vertically with and longitudinally of the table; of a guide-flange, and a gravity-operated latch adjacent said flange and adapted to limit the longitudinal movement of the stop, said latch being so disposed as to permit the stop to pass the latch during the downward vertical movement of the table.
2. In a mortising-machine the combination with a vertically-movable table and a stop movable therewith and longitudinally of the table; of a flange adjacent the table and constituting a guide for the stop during its vertical movement, and a latch for limiting the longitudinal movement of the stop prior to its upward movement, said latch being so disposed as to permit the stop to pass it upon the return or downward movement of the stop.
3. In a mortising-machine the combination with a vertically-movable table and a stop movable therewith and longitudinally thereof; of a latch pivotally mounted to swing in a vertical plane and adapted to limit the longitudinal movement of the stop prior to its upward movement, and means for shifting the latch into position to permit the stop to pass the same upon its return or downward movement.
4. In a mortising-machine the combination with a vertically-movable table and a stop movable longitudinally thereof and carried thereby; of a flange adjacent the table and constituting a guide for the stop during the vertical movement thereof, a latch adjacent the guide and adapted to limit the longitudinal movement of the stop prior to the vertical movement thereof, and means for actuating said latch to permit the stop to pass it during the completion of the vertical movement of the stop.

5. In a mortising-machine the combination with a vertically and longitudinally movable slide and a stop adjustably connected thereto; of a flange constituting a guide for the stop, a latch movably mounted adjacent one end of the flange, means for holding the latch normally spaced from the flange, said latch being disposed within the path of the stop during the vertical movement there-

of in one direction and in rear of the stop during the movement thereof in the opposite direction.

6. In a mortising-machine the combination with a vertically-movable table, a slide movable longitudinally thereon, and a stop carried by the slide; of a flange disposed adjacent the table and constituting a guide for the stop during the vertical movement of the stop and table, and a gravity-operated latch disposed below the guide-flange and normally spaced therefrom, said latch being arranged to be contacted by and to limit the longitudinal movement of the stop, and to release said stop during the completion of a vertical movement thereof.

7. In a mortising-machine the combination with a vertically-movable table, a slide thereon, and a stop adjustably connected to the slide; of a flange constituting a vertical guide for the stop, a latch, means for holding one end of the latch normally spaced a predetermined distance from the end of the flange, and gravity-operated means for returning the latch to said normal position after it has been shifted a greater distance from the flange, the stop being disposed to bear against and be limited in its longitudinal movement by the latch and to pass said latch during the completion of the vertical movement of the stop.

8. In a mortising-machine the combination with a vertically-movable table, a longitudinally-movable slide thereon, and a stop adjustably connected to the slide; of a flange constituting a vertical guide for the stop, said flange having a recessed end, a strip pivotally mounted below the flange and having a weighted end, said strip having one end normally spaced from, but adapted to be forced into, the recessed end of the flange, and gravity-operated means for holding the weighted strip in normal or spaced position, the stop being limited in its longitudinal movement by the strip and disposed to force the same into the recess, said strip adapted to release the stop during the completion of its vertical movement.

9. An attachment for mortising-machines comprising a guide-strip adapted to be secured to a vertically-movable table, a slide thereon, a stop-block secured upon the slide, a stop adjustably connected to the slide, a guide-flange, means for securing said flange to a fixed portion of a mortising-machine, and a gravity-operated latch pivotally secured adjacent, and normally spaced from one end of the flange, said latch being disposed to limit the longitudinal movement of the stop and to permit said stop to pass during the completion of its vertical movement.

10. An attachment for mortising-machines comprising a guide-strip adapted to be secured to the vertically-movable table

- of a mortising-machine, a slide thereon movable at an angle to the direction of movement of the table, a rod extending longitudinally of and movable with the slide, a stop adjustably mounted on the rod, a flange, means for securing the same to a fixed portion of a machine and in the path of the stop, said flange having a recess in the end of that side thereof first contacted by the stop, a strip pivotally mounted adjacent said end of the flange, and gravity-operated means for holding said strip normally spaced from the recessed end of the flange, said strip adapted when under pressure to be seated within the recessed end.
11. In a mortising-machine the combination with a vertically-movable bed; of a longitudinally-movable slide mounted thereon, a stop extending from the slide, and means fixed upon the machine for stopping the longitudinal movement of the stop and slide prior to each vertical movement of the table and for releasing said stop and slide during the completion of each vertical movement.
12. In a mortising-machine the combination with a vertically-movable table, a slide thereon, a rod disposed longitudinally upon and movable with the slide, and a stop adjustably secured upon the rod; of means fixedly secured to the machine for automatically stopping the longitudinal movement of the slide and stop prior to the vertical movement of the table and for releasing the stop and slide during the completion of said vertical movement.
13. The combination with a guide-flange and a gravity-controlled latch disposed therebelow and normally spaced therefrom; of a vertically-movable guide-strip, a horizontally-movable slide thereon, a rod secured to and movable with the slide, a sleeve ad-

justably mounted on the rod, and a plurality of fingers extending rearwardly from the sleeve and constituting stops, said stops adapted to successively contact with and be released by the latch prior to and during the completion of the vertical movement of the fingers respectively.

14. An attachment for mortising-machines comprising a base, a guide-flange extending therefrom and having a recessed end, a strip pivoted upon the base and having one end adapted to be seated within the recessed end of the flange, said strip having integral gravity-operated means for holding the same normally spaced a predetermined distance from the recessed end of the flange, a weight secured to and movable with the strip, said weight permitting the strip to be tilted a greater distance from the recessed end and adapted to return it to its position of normal spacing, and work-gaging means controlled by the guide-flange and latch.

15. In a mortising-machine the combination with a guide-flange and a latch movably mounted thereon and normally spaced therefrom; of a stop movable horizontally to shift the latch into alignment with the guide-flange and movable vertically to release the latch, and means upon the latch for shifting the same to direct the stop thereover upon the completion of its vertical movement.

In testimony that I claim the foregoing as my own I have hereto affixed my signature in the presence of two witnesses.

WILLIAM JAMES HAYDEN.
